GEORGE C. SOULE AND JOHN B. WOODBURY, OF SOUTH PORTLAND, MAINE, ASSIGNEES
TO MAINE STEEL PRODUCTS COMPANY, OF PORTLAND, MAINE, A CORPORATION OF
MAINE

SNOWPLOW

Application filed August 1, 1930. Serial No. 472,237.

This invention relates to snow plows, and particularly to the construction of the V or nose thereof. Although not specifically limited to such use, our invention is especially effective with truck-propelled plows, and in the further discussion thereof herein, we shall refer to it as applied to a truck plow. It will be understood, however, that this treatment is purely illustrative and in no way limiting.

10 Snow conditions in truck plowing as in all other kinds of truck plowing are extremely variable.

Two specific conditions constantly being met in truck plowing are not only variable but opposing in their requirements for plow design. When plowing moderate depths of snow at speed, the object of the truck plow is to throw the snow as far as possible off the road in order that it may neither have to be handled again nor make side banks which tend to cause re-drifting and blocking of the road.

The truck plow which would most efficiently throw the snow off the road would be constructed with a sharp outward overhang at the top of the V so that as the loose snow is forced upward by the speed of the V it strikes this overhang and is shot out to one side with great velocity. But through accident, neglect or for many other reasons snow may have accumulated, settled and frozen in great depth before the truck plow starts to move it in which case the sharp outward overhang, which would make the most effective snow throwing speed plow, cramps the deep heavy snow and makes it difficult for the truck plow to penetrate.

For such a condition of deep heavy snow a plow without the sharp outward overhang would be more efficient and would penetrate the drifts where the speed plow would cramp because the absence of sharp outward overhang would permit the deep heavy snow to roll up past the top of the V as in a tractor plow which is primarily designed for deep snow.

The result in prevalent snow plow design has been to enforce a compromise design which is neither the best for throwing snow at speed nor the best for penetrating deep

drifts because the logical design for the one purpose is opposing in principle to the logical design for the other, and because efficiency in the one field constitutes deficiency in the other field. Heretofore the practical plows have sacrificed some of the qualities necessary to efficiency under each condition in order to cope moderately well with both.

To the end therefore of providing a snow plow which will be capable of operating with complete efficiency regardless of which of these two snow conditions are met, we have devised our present invention.

According to it, the plow V or nose is of dual purpose, presenting first a snow rolling V with only sufficient outward overhang at the top to roll deep snow effectively without cramping but on which V may be superimposed when desired a detachable snow throwing superstructure designed to give the maximum of snow throwing qualities at speed and having its surface formed as a continuation of the surface curve of the main portion of the mouldboard. The snow rolling V portion is designed to lift and roll the snow higher than itself being efficient for heavy snow conditions, deep hard drifts and in general for heavy duty work where the depth or resistance of the snow reduces the speed and causes the propelling truck by reason of reduced speed to function similarly to a tractor. The snow rolling V should be specifically designed for penetrating snow depths greater than the height of the V without cramping, and to avoid cramping in deep snows must have only a small amount of outward overhang at the top so that the snow can roll smoothly upward in a direction approximating the vertical and so lift and pile the snow removed on the top of the banks higher than the V. For the lighter snows or less compacted falls where speed can be maintained it is important that the plow throw the snow sharply outwardly in a direction inclined toward the horizontal and low enough and far enough to the side so that it will not cover the windshield or obscure the vision of the operator which would be inevitable if a plow of the snow rolling type were operated at high speed.

Our invention thus conceives of the problem in terms of the conditions to be met so that the plow driver can quickly and conveniently adapt the plow to the conditions encountered.

As illustrative of our invention we show in the accompanying drawings a truck-propelled snow plow equipped with a dual purpose V or nose constructed in accordance with our invention. In such drawings:

Fig. 1 is a front view thereof.

Fig. 2 is a fragmentary plan, and

Fig. 3 is a section on the line 3—3, of Fig. 1.

We have indicated generally at 1 a snow rolling V or nose, the curved mouldboards of which have only sufficient outward overhang at the top to roll deep snow effectively without cramping.

Superimposed upon the V is a detachable snow throwing superstructure, indicated generally at 2, of such design as to give the maximum snow throwing qualities at speed, the surface of such super-structure being formed generally as a continuation of the surface curve of the main portions of the mouldboards, and designed with so considerable an outward overhang as to deflect the snow lifted by the V at speed and throw it sharply to one side.

Such superstructure 2 may be variously constructed and variously mounted detachably on the V or nose 1. As here shown it takes the form of a pair of converging strips 2¹ of the desired curvature which are flanged as at 2² and bolted or otherwise detachably assembled as at 3 on the flanged upper edges 1¹ of the mouldboards 1.

At their converging ends, the strips 2¹ may be united by an overlapping insert 4 which may be welded to one of the strips and bolted to the other. Obviously, of course, the strips may be joined at their apex in any other suitable manner.

In plowing moderate depths of snow at speed, the snow throwing superstructure 2 is mounted on the snow rolling V or nose 1 and so mounted affords that sharp outward overhang at the top of the V so necessary in dealing with such a snow condition.

In plowing deep heavy snow, the superstructure 2 is removed, so that the nose may penetrate the drifts without cramping.

It will be understood that in the foregoing discussion where we have referred to curves that we do not intend to limit ourselves to continuous curves as such, as obviously mouldboard surfaces might be formed with a series of angles or with combinations of angles and curves.

Various modifications in design, structure and manner of assembling may obviously be resorted to within the limits of the appended claims.

What we therefore claim and desire to secure by Letters Patent is:

1. Means for adapting the curved mouldboards of a snow plow designed for deep heavy snow for plowing moderate depths of snow at relatively high speeds, comprising a superstructure of relatively sharp outward overhang detachably mounted upon the mouldboards and constituting substantially a continuation of the surface contour of the mouldboards.

2. The combination with the curved snow rolling mouldboards of a snow plow designed for effective plowing in deep heavy snow, of a snow throwing superstructure of relatively sharp outward overhang detachably mounted upon the mouldboards and constituting substantially a continuation of the surface curvature of the mouldboards whereby to adapt the plow to effective plowing of moderate depths of snow at relatively high speeds.

3. The combination with the snow rolling curved mouldboards of a snow plow designed for effective plowing in deep heavy snow, of a snow throwing superstructure of relatively sharp outward overhang comprising a pair of convergent strips detachably mounted upon the upper edges of the mouldboards and constituting substantially a continuation of the surface contour of the mouldboards.

4. The combination with the curved snow rolling mouldboards of a snow plow designed for effective plowing in deep heavy snow, of a snow throwing superstructure of relatively sharp outward overhang comprising a pair of convergent strips detachably mounted upon the upper edges of the mouldboards and constituting substantially a continuation of the surface contour of the mouldboards, and an insert overlapping the converging ends of said strips and rigidly secured thereto.

In testimony whereof we affix our signatures.
